UNITED STATES PATENT OFFICE.

THOMAS E. CHERRY, OF BOSTON, MASSACHUSETTS.

ADDING MACHINE.

Application filed August 24, 1921. Serial No. 494,998.

To all whom it may concern:

Be it known that I, THOMAS E. CHERRY, a citizen of the United States, residing at Boston, in the county of Suffolk and State of Massachusetts, have invented new and useful Improvements in Adding Machines, of which the following is a specification.

This invention has for its chief object to provide an attachment whereby an adding-machine, the carriage and platen of which are not automatically reciprocated endwise, may be quickly and conveniently converted into a so-called shuttle machine, in which the carriage and platen are automatically reciprocated when such reciprocation is desired.

The invention is embodied in the improvements which I will now proceed to describe and claim.

20 Of the accompanying drawings forming a part of this specification,—

Figures 1 and 2 are side elevations of an adding-machine embodying the invention, the typing mechanism excepting the platen being omitted.

Figure 3 is a rear elevation of the same. Figure 4 is a fragmentary rear elevation.

Figure 5 is a perspective view of the carriage-unlocking attachment hereinafter described.

Figure 6 is a front side view of the cam-operated lever hereinafter described.

Figure 7 is a section on line 7—7 of Figure 6.

35 Figure 8 is a rear side view of the cam-operated lever.

The same reference characters indicate the same parts in all of the figures.

To illustrate my invention I have shown 40 certain elements of the well known Wales adding machine, and have designated said elements by reference letters, the elements in which my invention is embodied being designated by reference numerals.

45 *a* represents the carriage in which the impression roll or platen *b* is journaled, said carriage and platen being movable longitudinally and guided by the usual guiding members *c*, *c*, fixed to the frame *d*. *e* represents the rock-shaft which is rocked in bearings in the frame by the alternate action of a hand lever *f* movable by the operator to turn the rock-shaft in one direction, and a spring *g*, secured at one end to the frame, and at the other end to an arm *h* on the rock-shaft, the spring turning the rock-shaft

in the opposite direction when the lever is released. The plated *b* is rotated step by step by the usual mechanism, which includes a push-rod *j* having an end face *j'* (Figure 60 1), and a transverse bar or carriage rod *k*, supported by arms *l* and *m*, which are pivoted at *o*, *o* to the carriage. The end face *j'* normally contacts with the carriage rod (Figure 2). The arm *l* is the longer arm of a bell-crank lever, to the shorter arm *l'* of which is pivoted an arm *l''*, carrying the usual pawl *t*, cooperating with a ratchet *u* on the platen to rotate the latter step by step.

The carriage *k* is moved laterally in one direction to cause a partial rotation of the platen by an outward movement of the lever *f* from the position shown by Figure 1, to that shown by Figure 2. The lever *f* is 75 connected with the push-rod *j* in such manner that an outward movement of the lever causes an inward movement of the push-rod in the direction of arrow *x* (Figure 2), this movement causing the end face *j'* of the 80 push-rod to move the carriage rod *k* in the same direction, and thus impart a platen-rotating movement to the pawl *t*. When the lever *f* is returned by the spring *g* to the position shown by Figure 1, the push-rod *j* is moved outward, and allows the carriage rod *k* to be moved by gravity in the same direction, the pawl slipping back on the ratchet. The connections between the push-rod *j* and the lever *f* include a rocker-arm fulcrumed 85 at *s* on the frame *d*. The rocker-arm is pivoted at one side of its fulcrum by a pin *s'* to the push-rod, and at the opposite side of its fulcrum by a pin *s''*, to one end of a link *f'*, the opposite end of which is pivoted by 95 a pin *f''* to the lever *f*. Heretofore, the rocker-arm has served only as an element of the connections between the lever *f* and the push-rod, the lower end of the rocker-arm being at the pivot-pin *s''*. I have substituted for the usual rocker-arm, a longer arm 100 *23*, the lower end portion of which is extended below the pin *s''*, the extended rocker-arm performing another function, as hereinafter described.

The carriage *a* has the usual rod *p*, which is fixed at its ends to the carriage and is parallel with the platen *b*. By the employment of the mechanism described, I am able to transmit reciprocatory movements to the 110 carriage and platen, when such movements are desired, smoothly and equally in all steps

of movement, without shock or jar at the end of movement in either direction. This is due to the cam 16, 17, and the lever which transmits movement from said cam to the carriage. With this structure, the operating mechanism has no part or member which stops on a dead center, or causes a jar. My invention is embodied in the extended rocker-arm 23, and in the mechanism next described, preferably constituting an attachment which is applicable to a machine comprising the elements above described, and constituting a simple means for automatically reciprocating the carriage and platen endwise, as in so-called "shuttle" adding machines; for varying the length of the stroke or reciprocating movement of the carriage or platen, so that the paper constituting the record sheet or strip may be moved edgewise in some cases farther than in others; for conveniently disconnecting the carriage from the automatic mechanism which reciprocates it, so that the carriage and platen may be moved endwise by hand; for automatically disconnecting the platen from the mechanism which rotates it, so that the platen will be non-rotating during a predetermined period, and will be rotated step-by-step during another period; and for manually displacing the usual member which normally prevents movement of the carriage from left to right to permit such movement when it is desired.

12 represents a base plate or base extension which is attached by bolts 13 to the usual base d' supporting the frame d , said bolts being substituted, in the type of machine here shown, for two of the usual supporting feet d^2 , the feet at the rear portion of the base being removed and replaced by the bolts 13. Fixed to the base extension 12 is an upwardly projecting frame 14, having bearings for a shaft 15, extending parallel with the platen. Mounted to turn loosely on the shaft 15 is a carriage-reciprocating cam, comprising a cylinder 16, having a continuous cam groove, 17, and hereinafter referred to as the carriage cam. To one end of the carriage cam is fixed a ratchet 18, engaged by pawls 19, which are pivoted to a disk 20. Said disk is fixed to a pinion 21, which is rigid on the shaft 15. The carriage cam is intermittently rotated by mechanism which includes a rack 22, meshing with the pinion, and movable in a fixed guide 22^a, the extended rocker-arm 23 above described, and a link 26, connecting the rocker-arm with the rack, said arm being provided with a slot 27, receiving a stud 28, which is adjustable in the slot to vary the movement imparted to the rack. When the lever f is moved forward by the operator, the rack 22 is moved to the position shown by Figure 2, and rotates the pinion 21 and the ratchet 18 fixed thereto, in the direction required

to cause the ratchet teeth to slip on the pawls 19, rotation of the carriage cam being now prevented by a convex-ended spring-pressed detent 30 (Figures 3 and 4), engaging either of two concave recesses 31 in one end of the carriage cam. When the lever f is moved backward by the main spring g the rack is moved in the direction required to cause the teeth of the ratchet 18 to positively engage the pawls 19, and partly rotate the carriage cam.

Movement is communicated from the carriage cam to the carriage by a lever which is of variable length, to vary the extent of the movement imparted to the carriage, and is adapted to be rendered inoperative to permit endwise movement of the carriage by hand. Said lever includes an inner member 33 having a fulcrum stud 34, journaled in a bearing 35, on the frame 14, and a tapered trundle roll 36, entering the groove 17 of the carriage cam; an intermediate member 37 having studs 38 which are slideable in slots 39 in the inner member, and an outer member 40, connected at its lower end by a hinge 41 to the lower end of the intermediate member, and provided at its upper end with a tapered stud 42, having a trundle roll 42^a, and adapted to enter either of a plurality of slots 43 in a plate or flange 45, connected by clamps 44 with the carriage-rod p .

The said lever is adjustable by moving the intermediate member 37 endwise on the inner member 33, this movement being preferably effected by means of an adjusting screw 47, journaled in an ear 48, fixed to the inner member 33, and an ear 49, fixed to the intermediate member and extending through one of the slots 39, said ear having a tapped orifice engaging the thread of the screw 47. A knurled head 50 on the adjusting screw permits the rotation of the latter.

The intermediate member 37 has an outwardly projecting curved ear 51, passing through a slot 52 in the outer member 40. To said ear is pivoted a cam 53, having a handle 54, and adapted to press the outer member against the intermediate member, as shown by full lines in Figure 7, and to be displaced to permit the outer member to be forced outward by a spring 55, as shown by dotted lines, the trundle-roll 42^a being thus withdrawn from engagement with the carriage.

The means for preventing rotation of the platen during a predetermined period, and causing it to rotate step-by-step during another period, includes an arcuate cam rib or projection 57 on the carriage cam, a roller 58 in the path of said cam rib and attached to an arm 59 projecting outwardly from a rock-shaft 60, carried in a vertical bearing 61, fixed to the frame 14. At the upper end of the shaft 60 is a disk 62, having mounted

thereon a roller 63, adapted to engage the carriage-rod *k* and move the same sidewise to a rear position, thus rendering it inoperative, or preventing it from occupying a position where it can be actuated to impart rotation to the platen. When the cam rib 57 is in the position shown by Figure 1, it is out of contact with the roll 58, so that the rod-engaging roller 63 is loosely supported and permits the carriage rod *k* to assume a position rendering it operative. When the cam rib encounters the roller 58, the rod-engaging roller 63 is pressed and positively held against the carriage-rod *k*, and holds the latter in an inoperative position.

The parts are so proportioned that the platen carriage rod *k* will only be moved by the push rod *j* at each alternate forward movement of the handle *f*. During the feeding motion of the platen by the push rod *j* the carriage will be stationary. As the handle *f* returns to the position shown in Figure 1, the cam 16 will, through the lever 37, move the carriage in one direction. This will position the cam 57 so that the carriage rod *k* will be held beyond the path of the push rod *j* when the handle *f* is next drawn forward and therefore the platen will not be rotated until after the cam 16 and the lever 37 have returned the carriage to its former position and the handle is again actuated.

The usual locking lever *r* is provided, whereby the carriage is locked against movement in its guides *c*, when the locking lever is in its operative position shown by Figure 1, and is released and permitted to move endwise when the locking lever is in its inoperative position shown by Figure 2.

I have provided an attachment readily applicable to the carriage, for moving the locking lever *r* to, and confining it in its inoperative position.

Said attachment is shown separately by Figure 5, and includes a bar 79, having hooked flanges 80 and 83 at its ends, adapted to engage front and rear portions of the carriage, a set screw 81 engaged with the flange 83, and adapted to bear on an edge portion of the carriage, and a cam 78, fixed to a stud 85 which is journaled in the bar 79, and bears against the forward edge of the locking lever *r*. The cam is provided with a knurled knob 86, whereby it may be turned.

When the cam 78 is turned to the position shown by Figure 2, it moves the locking lever to its inoperative position. When the cam is turned to the position shown by Figure 5, it permits the locking lever to assume its operative position shown by Figure 1.

The carriage-reciprocating mechanism in which my invention is embodied may be installed in a machine not provided with

means for automatically reciprocating the carriage and platen endwise, by substituting the extended rocker-arm 23 for the short rocker-arm with which the machine was originally provided, removing the supporting feet *d*² from the rear portion of the base *d*', attaching the base plate 12 to the base *d*' by the bolts 13, connecting the link 26 with the rocker-arm, and securing the slotted flange 45 to the rod *p* by the clamps 44.

To install the described attachment in an existing machine, it is necessary to first remove the shaft forming the fulcrum *s*, remove the previously used rocker-arm and substitute therefor the extended rocker-arm 23, the said shaft being then replaced.

Remove the two rear existing feet corresponding to *d*², and place the extension base carrying the frame 14, and other mechanism, in place, and secure by means of bolts 13. When the base plate 12 is put in place, the rack 22 and the link 26 are inserted into the machine, and the link 26 is attached to the lever 23 by means of the stud 28.

Slip the clamps 44 over the rod *p*, and secure in place by set screws.

Loosen the set screw of locking lever, release the bar and slip the bar over the side of the carriage, and find the correct position. Mark the point of contact of the set screw with the carriage and file cut a groove in the carriage to receive the end of the set screw. Place the bar again in position, and set up a screw-securing bar in position.

I claim:

1. An adding-machine comprising, in combination, a rotary platen; a movable carriage therefor; manually operated mechanism for rotating the platen step-by-step; and carriage-reciprocating mechanism including a carriage cam, a lever oscillated by said cam, a lever-engaging member on the carriage, and connections between said cam and the platen-rotating mechanism whereby the cam is rotated step-by-step to reciprocate the carriage.

2. An adding-machine substantially as specified by claim 1, said lever being provided with means whereby it may be separated from said lever-engaging member to permit manual reciprocation of the carriage.

3. An adding-machine substantially as specified by claim 1, said lever being of variable length to permit variation of the amplitude of movement imparted to the carriage by the lever.

4. An adding-machine substantially as specified by claim 1, the said platen-rotating mechanism including a rocker-arm having an extension, and the said connections being engaged with said extension.

5. An adding-machine substantially as specified by claim 1, the said platen-rotating

mechanism including a rocker-arm having an extension, and said connections including a ratchet coaxial with and fixed to said cam, a pinion coaxial with the cam and independently rotatable, a ratchet-engaging pawl movable by the pinion, a rack engaged with the pinion, and a link connected with the rack and with the rocker-arm extension, to reciprocate the rack and rock the pinion.

6. An adding-machine substantially as specified by claim 1, the said platen-rotating mechanism including a rocker-arm having an extension, and the said connections including a ratchet coaxial with and fixed to said cam, a pinion coaxial with the cam and independently rotatable, a ratchet-engaging pawl movable by the pinion, a rack engaged with the pinion, and a link connected with the rack and with the rocker-arm extension, to reciprocate the rack and rock the pinion, yielding means being provided for preventing rotation of the cam when the pawl is moving backward on the ratchet.

7. An adding-machine substantially as specified by claim 1, the said lever including an inner member having a fulcrum stud journaled in a fixed bearing and a cam-engaging trundle-roll; and an outer member adapted to swing toward and from the inner member, and provided with a stud adapted to separably engage the lever-engaging member on the carriage, the lever being provided with a spring adapted to displace the outer member from its operative position, and with means for confining the outer member in its operative position.

8. An adding-machine substantially as specified by claim 1, the said lever including an inner member having a fulcrum stud journaled in a fixed bearing and a cam-engaging trundle-roll; and an outer member adapted to swing toward and from the inner member, and provided with a stud adapted to separably engage the lever-engaging member on the carriage, the lever being provided with means for longitudinally adjusting, and for positively securing the outer member to vary the operative length of the lever.

9. An adding-machine substantially as specified by claim 1, the said lever being composed of an inner member having a fulcrum stud journaled in a fixed bearing, and a cam-engaging trundle-roll; an intermediate member longitudinally adjustable on the inner member to vary the length of the lever, means being provided for positively connecting said members; and an outer member hinged to the intermediate member and provided with a stud engaged with the lever-engaging member on the carriage.

10. An adding-machine substantially as specified by claim 1, the said lever being

composed of an inner member having a fulcrum stud journaled in a fixed bearing, and a cam-engaging trundle-roll; an intermediate member longitudinally movable on the inner member, manually operable means being provided for moving the intermediate member to vary the length of the lever; and an outer member hinged to the intermediate member and provided with a stud engaged with the lever-engaging member on the carriage.

11. An adding-machine substantially as specified by claim 1, the said lever-engaging member being a slotted plate or flange provided with clamping means whereby it is secured to a rod on the carriage.

12. An adding-machine comprising, in combination, a rotary platen; a movable carriage therefor; manually operated mechanism for rotating the platen step by step; and carriage-reciprocating mechanism including a carriage cam, a lever oscillated by said cam, a lever-engaging member on the carriage, connections between said cam and the platen-rotating mechanism whereby the cam is rotated step-by-step to reciprocate the carriage, the said platen-rotating mechanism including a rod which is laterally movable to impart a step-by-step rotation to the platen, automatic intermittently operating mechanism for periodically holding said bar in an inoperative position and preventing the rotation of the platen.

13. An adding-machine comprising, in combination, a rotary platen; a movable carriage therefor; manually operated mechanism for rotating the platen step by step; carriage-reciprocating mechanism including a carriage cam, a lever oscillated by said cam, a lever-engaging member on the carriage, connections between said cam and the platen-rotating mechanism whereby the cam is rotated step-by-step to reciprocate the carriage, the said platen-rotating mechanism including a rod which is laterally movable to impart a step-by-step rotation to the platen; and automatic mechanism for periodically holding said rod in an inoperative position, including a segmental cam rib on said cam, and a rock shaft journaled in a fixed bearing and having an arm in the path of said rib, and an eccentrically mounted member in the path of said rod, and movable by the rock-shaft and cam rib to confine the rod in an inoperative position.

14. An adding-machine comprising, in combination, a rotary platen; a movable carriage therefor; manually operated mechanism for rotating the platen step by step, said mechanism including a rocker-arm fulcrumed on the main frame of the machine and provided with an extension; a supplemental frame; means securing the latter to the main frame of the machine; and carriage reciprocating mechanism including a

- carriage cam journaled in bearings on the supplemental frame, a lever fulcrumed on the supplemental frame and oscillatable by said cam, a lever-engaging member having 5 clamping means engaging a rod on the carriage, and connections between said cam and the rocker-arm extension whereby the cam is rotated step by step to reciprocate the carriage.
- 10 15. In an adding-machine which includes a rotary platen, a carriage therefor, and a platen-locking lever on the carriage; an attachment for manually moving the locking lever to, and holding it in, its inoperative 15 position, comprising a bar having clamping means engaging portions of the carriage, and a manually movable cam journaled in said bar and bearing on the locking lever.
16. An adding machine comprising, in 20 combination, a frame, a reciprocatory platen carriage supported by the frame, a rotary platen carried by the carriage, manually operated mechanism for rotating the platen step by step, a lever fulcrumed on the frame 25 and having one arm engaging said cam and another arm engaging the platen carriage, and means controlled by the operating devices of the platen rotating mechanism for imparting step by step rotary movement in 30 one direction to the cam to actuate the lever and move the carriage in opposite directions.
17. An adding machine comprising, in combination, a frame, a reciprocatory platen
- carried supported by the frame, a rotary platen carried by the carriage, manually 35 operated mechanism for rotating the platen step by step, a lever fulcrumed on the frame and having one arm engaging said cam and another arm engaging the platen carriage, means controlled by the operating devices 40 of the platen rotating mechanism for imparting step by step rotary movement in one direction to the cam to actuate the lever and move the carriage in opposite directions, and means turning with the cam and adapted 45 to render the platen rotating means inoperative during alternate operations of the manually operated mechanism.
18. An adding machine comprising, in combination, a frame, a platen carriage, a 50 rotary platen in said carriage, manually operated mechanism for rotating the platen step by step, a cam supported to rotate about an axis substantially parallel to the axis of the platen, a lever fulcrumed on the frame 55 and having one arm engaging said cam and the other engaging the platen carriage, and means actuated by the operating devices of the platen rotating means for intermittently rotating the platen to cause said lever to 60 move the platen carriage in opposite directions.

In testimony whereof I have affixed my signature.

THOMAS E. CHERRY.
